UNITED STATES PATENT OFFICE

PARIS R. FORMAN, OF RAHWAY, NEW JERSEY, ASSIGNOR TO NATIONAL PNEUMATIC COMPANY, OF NEW YORK, N. Y., A CORPORATION OF WEST VIRGINIA

TREADLE-CONTROLLED DOOR

Application filed August 3, 1926. Serial No. 126,858.

This invention relates to treadle controls for doors. One of the objects of this invention is to provide apparatus disposed in passageways obstructed by doors adapted to be operated by the passage of a person therethrough to cause said doors to operate. Another object of this invention is the provision of apparatus as mentioned above adapted to control the operation of the doors regardless of the direction of passage of pedestrians therethrough.

Another object of the invention is the provision of treadle controlled doors in passageways, which are driven by motive means connected to the power circuit of the building in which it is used.

A still further object of the invention is the provision of devices adapted to be energized by the depression of pivoted treadle plates disposed in the floor of the passageway to cause the doors to open.

Another object of this invention is the provision of apparatus of this type, which is simple and easy to construct and efficient in operation and maintenance.

These and many other objects are obtained by apparatus embodying the principles of my invention as disclosed hereinafter.

This invention resides substantially in the combination, construction, arrangement and relative location of parts as will be clearly described hereinafter.

Referring to the drawings in which the same reference numerals are used wherever possible in the several views to indicate the same or similar parts, Figure 1 is a side elevational view of a barrier disposed in the passageway disclosing the motive means for operating it.

Figure 2 is a horizontal cross-sectional view of Figure 1, showing the motive means in dotted lines.

Figure 3 is a top plan view of the treadle structure and a cross-sectional view of the barrier disclosed in the passageway.

Figure 4 is a wiring diagram of the devices employed.

Figure 5 is a cross-sectional view of a modi-

fied arrangement using double passageways taken on the line 5—5 of Figure 6.

Figure 6 is a side elevational view of the form shown in Figure 5.

Figure 7 is an enlarged plan view of another method of mounting the treadle plates.

Figure 8 is a cross-sectional view on the line 8—8 of Figure 7.

The apparatus of this invention is devised to provide means for controlling barriers in passageways, adapted to be operated by the entrance of a person into the passageway. The main features comprise a treadle disposed in the floor of the passageway, which in the preferred form is sectionalized. The treadle plates are pivoted and are adapted upon depression by the weight of a pedestrian thereon to close a circuit to the electric motive means disposed above the barriers. When the motive means is energized the barriers open and remain open until the pedestrian has moved from the treadle plates when the switch returns to its normal position to cause the motive means to close the doors.

Referring to the drawings, the barriers in the form disclosed comprise a door composed of two sections 50 and 51 hinged together by the hinges 54. The section 51 is secured by means of the door straps 52 to the rotatable vertically mounted shaft 53. On the outer end of door section 50 is secured the mounting 55 for the door guide roller 56 which travels in and is guided by the member 57. The edge of the door section 50 is provided with the cushioning element 58 which operates with the cushioning element 59 on the door frame to prevent slamming of the doors. Disposed above the door is the electric door operating device 60, which is disclosed in my copending application, Serial No. 127,512 filed August 6, 1926. The motor 60 is connected by means of the arm 61 to the crank 62, rigidly attached to the upper end of the door shaft 53.

Disposed in the floor of the passageway is a treadle plate 63 which is pivotally mounted at one side on the element 64. Disposed adjacent the free end of the treadle plate is a square shaft 66, which is mounted so as to

be rotatable. Mounted at intervals on the shaft 66 are the short lugs 69 projecting under the free depressible ends of the sections of the treadle plate, so that when the free 5 end of any section of the treadle plate is rotated downwardly it engages with one of the lugs on the shaft 66 to cause it to rotate through a portion of a revolution. In all 10 the barriers or doors, there is attached to the shaft 66, an arm 65, the free end of which operates through the switch S secured to the door frame 81.

I have found in actual experience that the best form of construction comprises a 15 treadle plate made up of a plurality of sections as is shown in Figure 3. I have found also that the sectionalized form is more sensitive because the sections are lighter and are easily operated even by the weight of a 20 child. The door remains open as long as any one treadle plate remains depressed.

In Figure 4, I have shown the circuits for the motor 60, which in the form contemplated comprises an alternating current 25 motor adapted to be connected to the power circuit of the building in which the device is used. The Switch S comprises a vertical slidable rod 67, having mounted therein the switch fingers or bridging members 71, 72, 30 73, 74, 75 and 76. Mounted on the lower end of the shaft 67 is a spring 68, which maintains the switch in a position to cause the doors to be closed when no one is on the treadle plate 63. Operating in conjunction 35 with this switch are the knock out switches 77 and 78. The switch 79 is inserted in the feed line and serves to disconnect the apparatus from the power source when desired. When this switch is closed the circuit of Figure 4 illustrates the relative position of the 40 apparatus when the doors are closed. When the door is closing knock out switch 78 is opened and knock out switch 77 is closed. But just as the door completes its closing 45 operation it causes switch 78 to close and switch 77 to be opened. Since the switch S is in the position to close the circuit to the motor for door closing, it is, of course, evident that some means must be provided to 50 break the feed circuit when the door is closed, so that the motor will be disconnected from the power source. When a pedestrian steps on the treadle 63 with the equipment shown in the position of Figure 4, switch S 55 will be shifted to its other position causing the fingers 76, 75 and 74 to bridge their contacts and at the same time causing fingers 71, 72 and 73 to move out of contact with their circuit terminals. This operation of 60 the switch merely causes reversal of the current in the armature circuit of the motor 60, causing it to operate in a reverse direction with a result that the doors open. The movement of the motor will cause switch 77 65 to close and switch 78 to open, at the end

of the door movement, so as to interrupt the current to the motor. As soon as the pedestrians move out of the pasageways and all of the sections of the treadle plate return to normal position, switch S under the influence 70 of spring 68 returns to its normal position to reverse the armature current and cause the doors to close.

It is believed that it is not necessary to trace the paths of the currents during these 75 operations, since they will be at once evident to those skilled in the art. The whole function of the circuit is merely adapted to reverse the current in the armature of the motor and to break the circuit when the door is completely opened or closed. 70 represents a 80 resistance in the motor circuit and 70' represents an impedance to limit the current to the motor to prevent its damage when the circuit is first completed thereto.

I do not desire to be limited to the specific embodiment of the principles of my invention as I have disclosed them herein, since other forms of elements may be used. For instance a pneumatic motor could be used to 85 operate the doors. One form of such equipment is shown in Figures 5 to 8. In this form of the invention, I have shown the two pasageways A and B. Disposed in the passageway A is a door comprising the two hinged sections 3 and 4 mounted on the vertical shaft 6. In the passageway B is a door comprising the two hinged sections 1 and 2 mounted on the vertical shaft 5. The shafts 5 and 6 are supported by the door frame 9. Mounted on the upper end of the shaft 6 is a crank 8, pivotally connected to the link 7, and at its other end is secured to the crank on the pneumatic motor 20 which may be one of the many known forms of pneumatic motors. Disposed in the floor of the passageway is the 90 pivoted treadle plate 37, which is mounted to rotate about the angle iron or plate 38. Under its free end are mounted springs 39, which are seated in the plates 40. Attached 95 to the free end of the plate are the projections 41, which contact with the lugs 42 secured to the shaft 43, which is pivotally mounted in the members 44. Keyed to the shaft 43 is an arm 45 which cooperates with the rod 27 on the switch which is slidably mounted in the brackets 29 and 30. The arm 45 moves the rod 27 upwardly against the action of the spring 31 to cause the bridging plate 28 to 100 close the circuit to the contacts 35. The wires from these contacts are connected with a magnet valve which is well known in the art, and is usually used in conjunction with pneumatic motors. This magnet valve admits 105 fluid pressure to a valve puller which in turn permits fluid pressure to operate the pneumatic motor.

It will be noted that in this form of the invention a single treadle plate is disposed throughout the length of the passageway. It 110

may be mentioned that the magnet valve and valve puller are so constructed that when the circuit to the magnet valve is broken a reversal of operation occurs and the engine moves back to cause the doors to close.

To show in somewhat greater detail one method of mounting the sections of a treadle plate, Figures 7 and 8 have been included. The sections 37 of the treadle plate are provided at one end with the projection lugs 36 which rest on the angle iron 38, while at their other ends are provided the projections 41 which contact with the lugs 42, secured to the rotatable shaft 43. It will be seen that upon the depression of any one of the sections of the treadle plate against the action of the spring 39 the shaft 43 will be operated in a counter-clockwise direction, see Figure 8, to cause the outer end of the arm 45 to move upwardly. The movement of this arm will operate any suitable switch, such as described above.

It will be evident from the foregoing description that I have embodied in my apparatus a number of novel features which are of considerable importance. I am aware that many changes in the detail of construction and arrangement of parts will suggest themselves to those skilled in the art, and I do not wish therefore, to be limited to the particular construction of features disclosed herein for purposes of illustration, but rather to the principle of my invention as defined below.

What I seek to secure by United States Letters Patent is:

1. In an automatic door operating apparatus, the combination with a passageway having doors therein and electrically operated means for opening said doors, of a treadle comprising a plurality of sections disposed in said passageway with several sections on each side of the door and switch means operated by the depression of any of said sections for actuating said door opening means.

2. In an automatic door operating device the combination with a passageway having doors therein and means for operating said doors, of a plurality of plates in said passageway adapted to be displaced by the passage of a person through the passageway, a single switch adapted to be closed by the displacement of any one of said plates whereby said means is caused to open said doors, and means for returning the plates to normal position after the passageway is clear to shift said switch whereby the doors are operated to close.

3. In an automatic door operating device the combination with a passageway having doors therein and means for operating said doors, of a plurality of pivoted plates in the passageway, a shaft disposed adjacent the free ends of the plates and adapted to be ro-

tated by movement of any one of said plates, a switch for controlling said means, and means on said shaft to close said switch when the shaft is rotated to cause the doors to open.

4. In an automatic door operating device 70 the combination with a passageway having doors therein and means for operating said doors, of a pivoted plate in the passageway, a shaft disposed adjacent the free end of the plate and adapted to be rotated by movement of said plate, a switch for controlling said means, means on said shaft to close said switch when the shaft is rotated to cause the doors to open, and means for returning said plate to normal position when the plate is free of weight whereby the switch is opened so that the means for operating the doors close them.

5. In an automatic door operating system 85 the combination with a passageway having doors therein and electric motor means for operating the doors, of treadle means in the passageway comprising a plurality of pivoted plates mounted in the floor thereof on each side of the doors, single switching means controlled by the depression of any plate for controlling said electric motor means to cause the doors to open, and means operated by the movement of the doors to break the circuit when the doors are fully opened or 95 closed.

6. In an automatic door operating apparatus, the combination with a passageway having a door therein and power means for operating said door, of a treadle comprising a plurality of sections disposed in said passageway with several sections on each side of the door, and control means operated by the depression of any one of said sections for actuating said power means for operating 105 said door.

7. In an automatic door operating device, the combination with a passageway having a door therein and means for operating said door, of a plurality of pivoted plates in the 110 passageway, a shaft rotatably supported adjacent the free ends of the plates, means co-acting with the free ends of the plates and mounted on said shaft for rotating the shaft when any one of said plates are depressed, and control means for actuating said means for operating the door.

8. In an automatic door operating device, the combination with a passageway having doors therein and means for operating said doors, of a plurality of plates in said passageway with several plates on each side of the doors adapted to be displaced by the passage of a person through the passageway, and a switch adapted to be closed by the displacement of one end of said plates whereby said means is caused to open said doors.

In testimony whereof I have hereunto set my hand on this 2d day of July, A. D. 1926.

PARIS R. FORMAN.
